(57) **CLAIM**

I claim the ornamental design for a floor rack, as shown and described.

DESCRIPTION

FIG. 1 is a perspective view of a floor rack;

FIG. 2 is a top plan view of the floor rack;

FIG. 3 is a front elevation view of the floor rack, the rear elevation view being an identical image to the front elevation view;

FIG. 4 is a right side elevation view of the floor rack, the left side elevation view being an identical image to the right side elevation view;

FIG. 5 is a bottom plan view of the floor rack; and,
FIG. 6 is a cross-section view of the floor rack taken across line **6-6** of FIG. 1.

Broken lines shown in the drawing views are included for illustrative purposes only, and form no part of the claimed design.
